UNITED STATES PATENT OFFICE.

ARTHUR C. BADGER, OF NEWTON, MASSACHUSETTS.

NONFREEZING FIRE EXTINGUISHER.

Application filed June 21, 1921. Serial No. 479,245.

The invention herein is concerned with fire extinguishers of the portable type in which pressure for expelling the liquid is developed by generation of a gas which will not support combustion, and the gas is generated by the mingling of chemical reagents effected at the instant when the extinguisher is put to use.

One object of the invention is to provide an extinguisher of this type which will not freeze even though exposed to the out-of-doors temperatures in the winter time.

A further object is to enable the mixture of reagents from which gas is evolved to be effected thoroughly in the minimum of time in order that large volumes of gas, with consequent high pressure may be instantly generated when the extinguisher is used.

In the embodiment of the invention which I have chosen for illustration in this specification the extinguisher is of that type in which the chemical reagents are, respectively, a salt of carbonic acid and an acid, and are brought into mixture with one another by inverting the entire extinguisher. But this illustrated embodiment is not intended as a limitation of the invention otherwise than as required by the terms and for the validity of the appended claims.

In carrying out the object of obtaining immunity from damage by freezing, I use as the liquid which is contained in the body of the extinguisher a liquid which will not freeze in the lowest temperatures occurring during the winter season in temperate latitudes, and is itself not inflammable. Various liquids or liquid mixtures having these qualities are known to the art. The chemical reagents are kept separate from the liquid and comprise, preferably, a dry carbonic acid salt and an acid in the liquid state. The dry salt container is so constructed as to afford ready access of the acid to a large proportion of the dry salt immediately upon the inversion of the extinguisher and spilling out of the acid from its container.

In the drawings forming a part of this specification,—

Figure 1 is in part a longitudinal section and in part an elevation of a fire extinguisher embodying the preferred form of my invention, shown in the upright position.

Figure 2 is a similar view showing a modification in the reagent holder of the extinguisher.

Figure 3 is a cross section of the dry salt container taken on line 3—3 of Figure 1.

Figure 4 is a view of the same character as Figure 1 representing the extinguisher there shown as inverted and in condition for use.

Figure 5 is a view similar to Figure 3 showing a modified construction of salt container.

Figure 6 is a fragmentary sectional view showing a specifically different form of bottle stopper.

Figure 7 is a cross section through the neck of the bottle equipped with the stopper shown in Figure 6.

Like reference characters indicate the same parts wherever they occur in all of the figures.

Referring first to Figures 1, 2 and 4, 10 represents the body shell of the extinguisher, which may be of usual form and of any size. 11 is the threaded neck which receives a detachable cap 12. Inside of the neck is a shoulder or abutment 14 which may be made either as a continuous ring or as a series of discontinuous lugs and from which is hung a holder 15 containing the chemical reagents. This holder is preferably of sheet metal having surrounding side walls and a bottom wall 16 imperforate and fluid tight except for the openings presently described. It may be made in two parts, or more, however, secured together by joints 17 of any desired character. It is supported on the abutment 14 by a shoulder 18 conveniently made as a ring surrounding and secured to the upper end of said holder. Said upper end is open in order to permit charging, but the cap 12 and the gasket by which said cap is lined securely closes its upper end when the cap is applied.

In the lower part of the container is placed a bottle 19 adapted to contain acid or whatever liquid may be used in any particular circumstances, and the part of the holder which receives said bottle is preferably shaped or constructed so as to prevent the bottle from having any considerable amount of side play. The bottle may have any shape and size and be made of any material suitable for the purpose in view, but preferably it has as wide a mouth as is possible in order that its contents may pour out freely and quickly when the extinguisher is inverted, and preferably also has external 105 110 115

shoulders whereby it may be held back by the cage or other retainer, hereinafter described, when inverted. And it should be made of a material such as glass, porcelain, 5 lead and so forth which is immune from attack by the contained reagent.

The upper part of the holder serves as a compartment for the charge of carbonic acid salt, and the bottom of such compartment is 10 made by a plate 21 which is mounted in the container above the acid bottle. Various modes of mounting such plate may be used, a convenient and inexpensive means for that purpose being here shown as consisting of 15 an indented and offset zone 20 in the side walls of the container. An important feature of the invention is that in the dry salt charge there are provided openings and channels adapted to permit entrance of the 20 acid into the interior of the mass of salt with possibility of immediate contact between the acid and salt at a large number of points of entrance at once. Hence in the 25 interior of the salt receiving space there is placed an interior partition 22 so made as to permit free passage of liquid through it and hold back a packed mass of powder or granular material. The partition is here shown as 30 made of wire mesh but it may also be made of perforated sheet metal or of any other equivalent construction. It is disposed in an approximately star-shaped outline as viewed endwise or in cross section (note Figure 3) with interior open spaces and is 35 placed so that such open spaces register with openings 23 in the plate 21. Thus when the salt charge is packed into the spaces of the holder surrounding this star-shaped 40 partition, the arms of the partition leave deep and numerous communicating open spaces which extend through the open plate 21. The salt may exist in the form of a 45 more or less fine powder or grains or pellets or lumps of any size. A rib 21^a rising from the plate and conforming to the required 50 outline of the partition 22 serves to locate the partition and may also serve as an anchorage to which the partition may be secured by soldering or otherwise.

In order to provide further points of entrance for the acid to the salt, the mass of the latter may be additionally cut into by indentations from the periphery of the charge, as shown in Figure 5, such indentations being established by the offsets 201 extending inwardly from an outer wall 200 of woven wire fabric, as shown in Figure 5. In this case the plate has additional slits or 55 openings 231 registering with the spaces defined by the indentations 201.

To the under side of the plate 21 there is connected by discontinuous ribs or bosses 24^a, a flange 24 or a series of arms internally threaded to hold a cage 25 which embraces 60 the neck of the acid bottle 19 and confines

and guides a stopper 26. The term "cage" is used here with a generic significance to include any structure, whether it has continuous or discontinuous walls or consists of a series of separated arms, which is so formed 70 and placed as to guide the stopper. Another function of the cage is to prevent the bottle from following the stopper when the extinguisher is overturned, wherefore the cage extends toward the shoulders of the bottle 75 (that is, the part where the body of the bottle widens from the neck) and terminates at a less distance from said shoulders than the distance through which the stopper is permitted to move upon overturning. The stopper may be made of lead, porcelain or any other material which is unaffected by the acid and has weight enough to cover the mouth of the bottle so as to prevent slopping of its contents when the extinguisher is 80 moved from place to place, and to fall away from the bottle and leave its mouth open when turned upside down.

Although the holder 15 is in the main impervious in order to prevent access of the 90 liquid contents of the extinguisher to the acid salt charge, it has openings 27 suitably arranged to permit escape of the gas generated by the mingling of the reagents. These openings may be arranged in any part of the 95 holder but are preferably near the top thereof, and preferably, also, tubes 28 extend from said openings beside the outer walls of the holder to ensure exclusion of the external liquid and to aid in the flow of the gas therefrom when the extinguisher is put to use.

When the extinguisher is inverted in the intended manner of use for extinguishing a fire, the stopper falls away from the mouth of the bottle but is arrested by the ribs or bosses 24^a so that it does not close the openings through the plate 21. The acid pours from the bottle and in falling passes around the stopper through whatever openings may be left in the sides of the cage and so on 105 through the slots 23, 201 (in the case where the latter slots are provided) into the open spaces within the dry salt charge. Being thus allowed to act upon a large proportion 110 of the salt contents at once, the reaction of the acid with the salt instantly generates large volumes of gas which escape through the openings 27 and rise through the liquid to the bottom of the extinguisher, applying heavy pressure to the liquid and impregnating it with carbonic acid gas. I have found in practice that a pressure great enough to throw a stream from the nozzle with which the extinguisher is equipped to a distance of 115 forty to fifty feet is generated without appreciable loss of time, and that substantially the same pressure is maintained by continuous evolution of gas until the liquid charge is exhausted.

I have not intended by anything in the 120

foregoing specification to limit my protection with respect to the chemical reagents and fire extinguishing liquid which may be used in an extinguisher embodying this invention. Any non-inflammable liquid or mixture of liquids which will not freeze in winter temperatures may be used, whether such liquid is water modified by admixture of a compound soluble therein which lowers its freezing point, or an entirely different compound than water; and for chemical reagents I may use bi-carbonate of soda as the dry salt and sulphuric acid, or any other reagents which are capable upon mixing of generating an inert gas, provided that the liquid reagent is a non-freezing liquid.

Figure 2 shows an alternative form of the invention which is essentially like that already described, but differs in that, instead of a single holder like the holder 15 containing both reagents there is provided an abbreviated holder 29 which contains the dry reagent package, the guide 30 for the bottle stopper and the holder 31 for the acid bottle being separably attached to said holder 29. The stopper guide 30 is substantially a tube which is screwed to a flange 32 attached to the bottom of the holder 29 and the bottle holder is substantially a cup screwed to the stopper guide. Wide enough spaces are left between the sides of the stopper guide and the stopper and through the bottom of the holder 29 to permit free flow of the liquid reagent in the bottle 19 when the extinguisher is turned upside down.

I do not confine my protection to the combination or use of a cage or other external guide for the stopper, but include also any construction in which the stopper has its own guide. Such a construction is shown in Figure 6 where the stopper 261 has a stem 262 extending through the mouth of the bottle and being long enough to serve as a guide for the whole movement of the stopper. And in this arrangement the result of arresting the stopper is performed by ribs 263 on what is normally the top side of the stopper, that is, the side toward the salt charge; such ribs coming in contact with the bottom of the plate and being equivalent in their function to the ribs or bosses 24^a. A separate bottle retainer 34 which may be loosely placed in the holder is appropriately formed to bear on the plate 24 or an adjacent part of the holder and to obstruct the shoulders of the bottle. This retainer may be made of sheet metal or of any other material in any form suitable for the purpose.

The term "bottle" is used in this specification with a broad significance to include any liquid container capable of being covered with a stopper.

What I claim and desire to secure by Letters Patent is:

1. A fire extinguisher comprising a body adapted to contain a fire extinguishing liquid, a holder mounted in the upper part of said body forming an inner compartment substantially closed against inflow of the said fire extinguishing liquid when the extinguisher is in its normal position, said inner compartment having an outlet through which gas may readily flow, a bottle for a liquid reagent contained in the lower part of said compartment, a package of a complementary reagent in dry granular condition, adapted to coact with the liquid reagent to generate gas confined in the upper part of said compartment, and perforated walls arranged within the mass of said granular reagent in a form providing open channels through which the liquid from said bottle may pass, upon overturning of the extinguisher, into contact with a large proportion at once of said mass.

2. A chemical fire extinguisher comprising an outer shell, an inner shell or holder mounted therein and defining an interior chamber having restricted communication with the surrounding space in a manner substantially preventing inflow of liquid, a container for a chemical reagent having permeable walls arranged with deep reentrant angles mounted in the upper part of said chamber, and a bottle for a liquid chemical reagent mounted in the lower part of said chamber.

3. A chemical fire extinguisher comprising an outer shell, an inner shell mounted therein and defining an interior chamber having restricted communication with the surrounding space in a manner substantially preventing inflow of liquid, a container for a chemical reagent having permeable walls arranged with deep reentrant angles mounted in the upper part of said chamber, a bottle for a liquid chemical reagent mounted in the lower part of said chamber, the stopper for said bottle normally resting on the mouth thereof, and a guide for the stopper secured within said chamber and arranged to prevent substantial dislodgment of the bottle when the extinguisher is overturned.

4. A fire extinguisher comprising a shell, an interior container having an acid receptacle in its lower part, a plate supported in said container above said receptacle and having openings through it, and interior walls of liquid-permeable material extending away from said plate and arranged to form compartments for reception of a granular reagent between and in alternation with open spaces into which liquid may flow from said acid receptacle.

In testimony whereof I have affixed my signature.

ARTHUR C. BADGER.
